UNITED STATES PATENT OFFICE.

ROMAIN DE BERSAQUES, OF SEATTLE, WASHINGTON.

EYE-OPERATING MECHANISM FOR DOLLS.

Application filed May 10, 1922, Serial No. 559,950. Renewed April 13, 1925.

To all whom it may concern:

Be it known that I, ROMAIN DE BERSAQUES, a citizen of the United States, residing at Seattle, in the county of King and State of Washington, have invented a certain new and useful Improvement in Eye-Operating Mechanism for Dolls, of which the following is a specification.

My invention relates to improvements in eye operating mechanism for dolls and the object of my invention is to provide an eye operating mechanism for turning the eyes of a doll from one side to the other when the doll is inclined sidewise from a vertical position.

Another object is to provide eye operating mechanism that is strong and simple in construction, cheap to manufacture, easy to install within a doll head of standard construction and not liable to get out of order even when subjected to rough usage.

A further object is to provide eye operating mechanism in which the eyes are turned from side to side by the use of a suspended weight that tends to hang in a vertical position when the doll is inclined to either side of the vertical.

Other and more specific objects will be apparent from the following description taken in connection with the accompanying drawings.

I accomplish these objects by devices illustrated in the accompanying drawings wherein Figure 1 is a view in vertical mid section showing a doll head within which is installed eye operating mechanism constructed in accordance with my invention.

Fig. 2 is a view in front elevation of the eyes and eye operating mechanism detached from the head of the doll.

Fig. 3 is a plan view on line 3, 3 of Fig. 2 and

Figs. 4 and 5 are views in front elevation showing the maximum positions that the eyes and eye operating mechanism may assume when the head of the doll is tilted to the right or to the left of the vertical respectively.

Referring to the drawings, throughout which like reference numerals indicate like parts, the numeral 7 designates a doll head of common form that is provided in the crown portion with an opening 8 through which mechanism in an assembled state may be inserted, said head being provided with

the usual openings, not shown, at the location of the eyes.

Rigidly secured within the nose of the doll head 7 is a socket 9 preferably of U shaped cross section for the reception of the lower end 10 of a normally vertical supporting bar 11, whose upper end is curved to fit the contour of the forehead and is rigidly secured to said forehead as by a body of cement or plaster of Paris 12 that may be plastered into the head in a soft state when the mechanism is inserted, and allowed to harden, the supporting bar 11 being thus securely anchored to the head 7.

Secured to the bar 11 is a rearwardly protruding U shaped clip 13 to which another clip 14 is pivotally connected by a transverse normally horizontal pivot pin 15. The clip 14 is integral with or otherwise rigidly secured to a downwardly protruding bracket arm 16 on the forwardly bent lower end of which is a fixedly secured cross bar 17.

Secured by pivots 19 to opposite ends of the fixed cross bar 17 are bracket members 18 that extend upwardly and rearwardly and are thence bent double and terminate in forwardly protruding ends to which eyeballs 20 are fixedly connected in any suitable manner. The rear ends of the brackets 18 are secured by pivots 21 to a movable cross bar 22 that is provided midway between its two ends with a downwardly protruding relatively fixed arm 23 which terminates in a forwardly extending portion 24, that projects through a slot 25 in an arm 26 whose upper end is pivoted to the upper end of the bracket member 16 and whose lower end is provided with a weight 27.

In operation when the head 7 is tilted sidewise either to right or left the weight arm 26 will tend to remain in a vertical position and by reason of its connection by means of parts 24 and 23 with cross bar 22 will cause said cross bar to move transversely relative to the eyeballs 20 and by turning the bracket members 18 on their pivots to turn the eyeballs 20 in a direction opposite to the direction in which the head is inclined. For instance if the head 7 is in an upright position the eyeballs 20 will appear to be directed straight to the front as shown in detached views in Figs. 2 and 3. If the head 7 is tilted to the right from the vertical position the supporting bar 11

which is rigidly connected with the head and the other parts that are fixedly secured to the supporting bar will be inclined as shown in Fig. 4, while the weight arm 26 5 will remain in a substantially vertical position and will turn the eyeballs 20 to the left, while if the head is tilted to the left from the vertical position the relatively fixed parts will be turned into the positions 10 shown in Fig. 5 and the eyeballs will be turned to the right.

By operating in the manner above described it will be seen that a doll may be caused to roll its eyes from one side to the other by tilting the doll from one side to the other of the vertical position.

The pivots 19 of the eye supporting brackets 18 are located on the prolongation of the vertical axis of the eyeballs so that 20 turning movement of the brackets will impart rotary movement on an axial line to said eyeballs.

If the head 7 is tilted rearwardly the weight 27 which will tend to hang in a vertical position will cause the eye supporting mechanism to be oscillated on the normally horizontal pivot pin 15 and the eyeballs to be turned downwardly relative to the face of the doll. If the head is tilted far enough 30 to the rear the pupils of the eyeballs 20 will pass entirely out of sight and will appear to be entirely closed. When the head 7 is again moved into a vertical position, the pupils of the eyeballs will again be visible.

The use of a fixed socket 9 in the nose of the doll head makes it easy to insert the eyes and eye operating mechanism into the head 7 in assembling the doll.

The several parts are simple in construction, easy to manufacture and assemble and are not liable to get out of order after they are placed in the head of a doll.

The sidewise or rolling movement of the eyes attained by this mechanism is especially entertaining and fascinating to children and gives a life like appearance to the doll.

The foregoing description taken in connection with the accompanying drawings clearly discloses the plan of construction and method of operation of this invention, but, while I have shown and described what I now consider to be the preferred embodiment of the invention it will be understood that the disclosure is merely illustrative and that such changes in the invention may be made as are within the scope and spirit of appended claim.

What I claim is:

The combination with a doll's head, of a 60 socket secured within the nose portion of said doll head, a supporting bar arranged to fit within said socket and to be cemented to the forehead portion of said doll head, a fixed bracket projecting rearwardly from 65 said supporting bar, an arm connected with said fixed bracket and protruding downwardly, a transverse bar supported by said arm, an eyeball supporting bracket pivoted to each end of said transverse bar, an eyeball secured to each eyeball supporting bracket, an actuating bar connecting said two eyeball supporting brackets, a weight arm pivotally connected with said fixed bracket, a weight on the lower end of said 70 weight arm and means connecting said weight arm with said actuating bar for moving said actuating bar to turn said eyeball supporting brackets in response to side- 75 wise tilting movement of said doll head.

In witness whereof, I hereunto subscribe my name this 13th day of April A. D. 1922.

ROMAIN DE BERSAQUES.
